BILLIARD TABLE

Philip E. Crossman, 1435 E. Mason,
Green Bay, Wis. 54301

Filed Mar. 8, 1972, Ser. No. 233,996

Term of patent 14 years

Int. Cl. D21—01

U.S. Cl. D34—3

FIG. 1 is a perspective view of the billiard table of my design.

FIG. 2 is a view of the ball return end of the billiard table of my design.

FIG. 3 is a view of the opposite end of the billiard table of my design from that illustrated in FIG. 2.

FIG. 4 is a side view of the billiard table of my design.

FIG. 5 is a top plan view of the billiard table.

FIG. 6 is a bottom view of the billiard table of my design.

I claim:

The ornamental design for a billiard table, substantially as shown and described.
